UNITED STATES PATENT OFFICE

148,079

DESIGN FOR A THERMOSTATIC CONTROL CABINET

Joshua Gordon Lippincott, Scarsdale, N. Y., assignor to Simmons Company, New York, N. Y., a corporation of Delaware

Application June 1, 1946, Serial No. 130,481

Term of patent 14 years

(Cl. D26—5)

To all whom it may concern:

Be it known that I, J. Gordon Lippincott, a citizen of the United States, residing in Scarsdale, in the county of Westchester and State of New York, have invented an improved ornamental Design for a Thermostatic Control Cabinet, of which the following is a specification, reference being had to the accompanying drawings, forming part thereof.

Fig. 1 is a perspective view of a thermostatic control cabinet embodying my new design;

Figs. 2 and 3 are, respectively, front and side elevational views; and

Fig. 4 is a top plan view thereof.

I claim:

The ornamental design for a thermostatic control cabinet, substantially as shown.

J. GORDON LIPPINCOTT.
